UNITED STATES PATENT OFFICE

108,553

DESIGN FOR A COMBINED LAMP AND FAN OR SIMILAR ARTICLE

Ernest G. Shinner, Chicago, Ill., assignor to Air-
O-Lite Corporation, Chicago, Ill., a corporation of Illinois

Application October 25, 1937, Serial No. 72,411

Term of patent 3½ years

To all whom it may concern:

Be it known that I, Ernest G. Shinner, a citizen of the United States and a resident of the city of Chicago, in the county of Cook and State of Illinois, have invented a new, original, and ornamental Design for a Combined Lamp and Fan or Similar Article, of which the following is a specification, reference being had to the accompanying drawing, forming a part thereof.

On the drawing:

Figure 1 is a side elevational view of the combined lamp and fan, with the shade raised apart from the standard showing my new design.

I claim:

The ornamental design for a combined lamp and fan or similar article as shown and described.

ERNEST G. SHINNER.
